UNITED STATES PATENT OFFICE.

JOHN W. VAUGHN, OF NOROTON HEIGHTS, CONNECTICUT.

POSTAL SCALE.

1,080,391.

Specification of Letters Patent.

Patented Dec. 2, 1913.

Application filed April 5, 1913. Serial No. 759,077.

To all whom it may concern:

Be it known that I, JOHN W. VAUGHN, a citizen of the United States of America, residing at Noroton Heights, in the county of 5 Fairfield and State of Connecticut, have invented certain new and useful Improvements in Postal Scales, of which the following is a specification.

This invention relates to scales of the type 10 commonly known as "postal scales" and it is the object of the invention to provide an improved structure of this character arranged in such manner that while no springs are employed, the necessity of manipulating 15 a poise is obviated and the weight of the matter being weighed will be readily indicated to the user.

It is a further object of the invention to 20 accomplishing the foregoing results in a structure that, while it may be very simply and cheaply made, will be extremely accurate.

Further objects and advantages of the invention will be set forth in the detailed description which now follows:

In the accompanying drawing, Figure 1 is 25 a side elevation of a postal scale constructed in accordance with the invention, and Fig. 2 is a sectional view upon line X-X of 30 Fig. 1.

Like numerals designate corresponding parts in both of the figures of the drawing.

Referring to the drawing, the numeral 5 designates a supporting base which carries a 35 standard 6. Pivoted at 7, to the upper end of this standard are the integral ears 8 (only one of which is shown) of a beam 9. This beam carries upstanding, divergent elements 10 which form a pocket for the reception of 40 the matter that is to be weighed.

The portion of the beam to the right of pivot 7 is longer than the portion to the left, to thereby counterbalance the weight of the 45 elements 10. A stop finger 11 is struck from the beam 9 and serves to limit the downward movement of the right-hand end of the beam.

A bracket 12 is secured by screws or like fastening devices 13 to the standard 6, though it is apparent that instead of making 50 these elements of two parts they may be in one piece if desired. This bracket is continued to form a web 14 which terminates in a vertically disposed head plate 15, this head plate lying at one side of the path of movement of the beam 9 and having its lower edge disposed at an angle to the upper face of

said beam when the latter is in a horizontal position. This plate has a plurality of openings 16 formed therein and at the lower sides of each of these openings, transverse wings 60 17 project from the head plate 15 and form a seating for wedge shaped weights 18 that are provided with recesses or pockets 19 in their under sides.

Pins 20 having their outer ends upturned 65 to engage in the pockets 19, project laterally from one side of the beam and when the matter to be weighed has been placed in the pocket formed by the members 10, the raising of the right hand end of the beam picks 70 up the weights one after the other in a manner that will readily be understood. By virtue of the fact that these weights are of wedge shape and that their extreme width is less than the width of the openings 16, it 75 follows that just as soon as the weights have been lifted free of the wings 17, all frictional engagement between the weights and the head plate is terminated. I am able to secure this advantage while at the same time 80 maintaining the head plate in such position with relation to the weights that matter indicative of the amount of the postage may be impressed upon the head plate as indicated at 20. Furthermore, the head plate 85 comprises merely a sheet of metal provided with the transverse wings. It may consequently be stamped out at a very small cost. Since the weights travel in the recesses formed in the head plate, it follows that they 90 are protected against accidental dislodgement.

From the foregoing description, it will be seen that simple and efficient means are herein provided for accomplishing the objects of 95 the invention, but while the elements shown and described are well adapted to serve the purposes for which they are intended, it is to be understood that the invention is not limited to the precise construction set forth, 100 but includes within its purview such changes as may be made within the scope of the appended claims.

Having described my invention, what I claim is:

1. In a device of the character described, 105 the combination with a support, of a beam tiltably mounted upon said support, a vertically disposed head plate located above and at one side of the line of travel of said beam, said head plate having a plurality of recesses formed in its under edge and which

- open at the bottom thereof and the side walls of which converge downwardly, a plurality of wedge shaped weights supported within said recesses, the lower edge of said head 5 plate lying at an angle with relation to the upper face of said beam when the latter is in a horizontal position, and means carried by said beam for successively engaging said weights.
- 10 2. In a device of the character described, the combination with a supporting member, of a beam tiltably mounted thereon, a bracket secured to said supporting member, a vertically disposed plane head plate carried by said bracket and having a plurality of openings formed therein which open at the bottom edge thereof, transverse wings carried by said head plate at the opposite sides of the lower portions of said openings, 15 a series of wedge shaped weights having seatings upon said wings, and a plurality of weight engaging members extending transversely to and carried by said beam, the lower edge of said head plate lying at an angle 20 with relation to the upper face of said beam when said beam is in a horizontal position, whereby said weight engaging members successively engage and lift said weights from the wings upon which they are seated.
- 25 3. In a device of the character described, the combination with a support, of a beam 30
- pivottally mounted upon said support, pocket forming members mounted upon one end of said beam, a plurality of transversely extending pins terminating in upturned ends, 35 said pins projecting laterally from one side of said beam, a bracket secured to said support beneath said beam, said bracket carrying a vertically disposed plane head plate which lies above and to one side of the line 40 of travel of said beam, the lower edge of said head plate lying at an angle with relation to the upper face of said beam when the latter is in a horizontal position, and said head plate having a plurality of openings 45 formed therein which open at the lower edge of said head plate, transversely extending, oppositely inclined wings at the opposed lower edges of said openings and wedge shaped weights seated between said wings 50 and having pockets in their under faces for engagement therein of the upturned ends of said pins when the beam rises, whereby said weights are successively lifted from their engagement with said wings. 55
- In testimony whereof I affix my signature in presence of two witnesses.
- JOHN W. VAUGHN.
- Witnesses:
- JAMES W. WHITE,
MARY W. PELTON.
